UNITED STATES PATENT OFFICE.

RAOUL J. GRUENBERG, OF SAN FRANCISCO, CALIFORNIA.

DESIGN FOR AN AUTOMOBILE-BODY.

55,461.

Specification for Design.

Patented June 15, 1920.

Application filed January 19, 1920. Serial No. 352,626. Term of patent 3½ years.

To all whom it may concern:

Be it known that I, RAOUL J. GRUENBERG, a citizen of the United States, and resident of the city and county of San Francisco, State of California, have invented a new, original, and ornamental Design for an Automobile-Body, of which the following is a specification, reference being had to the accompanying drawing, forming a part thereof.

In the drawing:

Figure 1 is a side elevation of the automobile body,

Fig. 2 is a rear end elevation, and

Fig. 3 is a front end elevation.

What I claim is:

The new and ornamental design for an automobile body substantially as shown.

In testimony whereof, I have hereunto set my hand this 7th day of January 1920 in the presence of the two subscribed witnesses.

RAOUL J. GRUENBERG.

Witnesses:
